UNITED STATES PATENT OFFICE.

CASPER H. DICKE, OF DOWNSERS GROVE, ILLINOIS.

WIRE GRIP.

Application filed February 24, 1922. Serial No. 538,890.

To all whom it may concern:

Be it known that I, CASPER H. DICKE, a citizen of the United States, residing at Downers Grove, in the county of Cook and 5 State of Illinois, have invented certain new and useful Improvements in Wire Grips, of which the following is a specification.

This invention relates to wire grips.

It is particularly adapted for use in the 10 running of telephone, telegraph and power system lines, although applicable for use in other fields. Such grips are ordinarily used to properly tension the wires between poles, etc.

15 One of the objects of this invention is to provide an improved wire grip.

Another object is to provide an improved grip in which the wire gripping jaws may be latched in open or wire receiving position.

Another object is to provide a grip in which the jaws may be frictionally locked in open position without manipulating any part of the tensioning tackle.

25 Another object is to provide a grip which is efficient, reliable, simple and inexpensive.

Other objects and advantages will herein-after appear.

Embodiments of the invention are illustrated in the accompanying drawings, 30 wherein

Fig. 1 is a top plan of a grip.

Fig. 2 is a side elevation partly in section, 35 showing the grip in open and closed positions.

Fig. 3 is an enlarged section through the latch for automatically holding the jaws in open position.

The grip has a relatively fixed jaw 1 and 40 a relatively movable jaw 2. These two jaws may be separated to open or wire receiving position and may be moved together to closed or wire clamping position.

Jaws 1 and 2 are pivotally interconnected 45 by a strap 3 and a lever 4. These pivotal connections cause the jaws to be maintained in a substantially parallel relation to increase the effective wire gripping surfaces.

Jaw 1 is somewhat longer than jaw 2 and 50 has a longitudinal closed slot 5 there-through. A pin 6 lies in and is movable along slot 5. A pair of operating links 7 are connected at one end to pin 6 and at the other end to lever 4. A draft device 8, 55 which ordinarily is in the form of a loop for attachment to the tensioning tackle used

by linemen, is connected to pin 6 on the outside of links 7.

A spring 9, which is coiled about a lug 10, 60 projecting from one of the links 7, has one end against a stop 11 on the same link and the other end against a shoulder 12 on lever 4. This spring yieldingly biases the jaws to closed position wherein pin 6 is toward the outer end of slot 5.

In order to open the jaws to receive the 65 wire, pin 6 is moved toward the inner end of slot 5 against the tension of spring 9. The toggle comprising links 7 and lever 4 is thus closed and the movable jaw is moved 70 away from the fixed jaw as shown by the dotted lines of Fig. 2.

A hole 13 is made through jaw 1 so as to lie behind links 7 when the jaws are open. Into hole 13 a ball 14 is set, and loosely retained in position by slightly upsetting the rim of the hole on one or both sides. The diameter of ball 14 is somewhat greater than the distance between the facing surfaces of links 7. When the jaws are opened, 80 by forcing pin 6 to the inner end of slot 5, links 7 are forced upon the ball and separated. The friction between the ball and links 7 and between the ends of the links and the ends of draft device 8 at pin 6, holds the jaws open against the force of spring 9. However, a slight pressure on lever 4 or a slight pull on draft device 8 overcomes the 85 friction, the jaws are released and spring 9 is free to close the same upon the wire.

90 Thus the jaws may be automatically locked in open position until the wire is placed therebetween, whereupon by the simple operation of pressing the toggle or tightening upon the tackle will unlatch the jaws. 95 The greater the pull upon draft device 8 the tighter the wire will be clamped between the jaws. The jaws are locked open irrespective of the angular position of the draft device and tackle.

100 Having described my invention what I claim as new and desire to secure by Letters Patent, is:—

1. A wire grip having a pair of relatively movable jaws for clamping a wire 105 between them, a draft device for attachment to tensioning tackle and associated with the jaws to cause the same to clamp the wire, and a ball for frictionally holding the jaws in non-clamping position.

110 2. A wire grip having a pair of relatively movable jaws adapted to be opened to re-

- ceive a wire and to be closed to grip a wire, a link pivotally associated with the jaws, a draft device connected to the link and acting therethrough to close the jaws, and a 5 friction element independent of the draft device and cooperating with one of the jaws and the link and acting to hold the jaws in open position irrespective of the angular position of the draft device.
- 10 3. A wire grip having a pair of relatively movable jaws adapted to be opened to receive a wire and to be closed to grip a wire between them, a draft device, a lever pivotally interconnecting the jaws, a link 15 interconnecting the lever and the draft device, and a friction element independent of the draft device associated with one of the jaws and acting upon the link to hold the jaws in open position irrespective of the 20 angular position of the draft device.
4. A wire grip having a pair of relatively movable jaws adapted to be separated to receive a wire and to be brought together

to clamp a wire between them, a lever pivotally interconnecting the jaws, a draft device, a link interconnecting the lever and the draft device, and a ball held by one of the jaws and acting upon the link to hold the jaws in open position.

5. A wire grip comprising a relatively fixed jaw with a slot therein, a relatively movable jaw pivotally connected to the fixed jaw, a lever interconnecting the jaws, a draft device, a pin passing through the slot in the fixed jaw and attaching the draft device thereto, a pair of parallel links interconnecting the pin and the lever and acting to communicate movement from the draft device to the movable jaw, and a ball held in the fixed jaw and over which the links move when the jaws are in open position and cooperating with the links to hold the jaws in open position.

In testimony whereof I hereunto subscribed my name,

CASPER H. DICKE.
